DESIGN FOR A PORTABLE BAR OR SIMILAR ARTICLE

Carl H. Hasche, Los Angeles, Calif.

Application February 16, 1945, Serial No. 118,003

Term of patent 7 years

(Cl. D33—19)

To all whom it may concern:

Be it known that I, Carl H. Hasche, a citizen of the United States and a resident of the city of Los Angeles, in the county of Los Angeles and State of California, have invented a new, original, and ornamental Design for a Portable Bar or Similar Article, of which the following is a specification, reference being had to the accompanying drawing, forming part thereof, in which:

Figure 1 is a pictorial view of a portable bar or similar article embodying my invention, the cover or tray member being shown separated from the portable bar in order more fully to describe the top portion of the same; and

Fig. 2 is a side elevational view thereof.

The side not illustrated in Fig. 2 is the same as that shown.

I claim:

The ornamental design for a portable bar or similar article, substantially as shown and described.

CARL H. HASCHE.
